CLAIM

The ornamental design for a massage device, as shown and described.

DESCRIPTION

FIG. 1 is a front, right, and top perspective view of a massage device showing my new design;
FIG. 2 is a rear, left, and bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is a second front, right, and top perspective view thereof, shown in an exploded state;
FIG. 10 is a third front, right, and top perspective view thereof, shown in an alternate configuration; and,
FIG. 11 is a rear, right, and top perspective view thereof, shown in a configuration of use.
The broken lines in the drawings depict portions of the massage device that form no part of the claimed design.
